UNITED STATES PATENT OFFICE.

WILLIAM N. FURTHMANN, OF CHICAGO, ILLINOIS, ASSIGNOR TO THOMAS H. TAPLEY,
OF GRAND RAPIDS, MICHIGAN.

LIQUID-FUEL BURNER.

1,135,679.

Specification of Letters Patent. Patented Apr. 13, 1915.

Application filed July 30, 1913. Serial No. 782,010.

To all whom it may concern:

Be it known that I, WILLIAM N. FURTHMANN, citizen of the United States, residing at Chicago, in the county of Cook and State 5 of Illinois, have invented a certain new and useful Improvement in Liquid-Fuel Burners, of which the following is a full, clear, concise, and exact description.

My invention relates to improvements in 10 liquid-fuel burners and to automatic regulators for the fuel supply.

The preferred construction illustrated in the accompanying drawings is one adapted particularly for use in connection with a 15 heating device such as shown in my co-pending application Serial No. 782,009, filed July 30, 1913, although it is not limited to such use.

In the drawings, Figure 1 is an elevation 20 partly in section of said preferred construction; Fig. 2 is an enlarged, sectional elevation of the needle valve; Fig. 3 is an enlarged, top plan view of the adjusting device for said valve; Fig. 4 is a top plan view 25 of the supporting arm; and Fig. 5 is a top plan view of the lever arm. Fig. 6 is an enlarged sectional view of a detail.

The burner 1 is provided with a conical recess which contains the liquid-fuel, the 30 base of said burner having a flanged rim 2 adapted to catch any of the liquid which overflows the top of the burner. Said burner is supported on a suitable frame comprising radial arms 3 carried by a supporting member 4, the latter constituting 35 the base of the combustion chamber. The frame 3 also carries a circular partition 5 having a cap 6 with an opening somewhat larger than the burner, through which opening air is supplied to the flame. A pair of 40 concentric tubes 7 and 8 project through the base of the burner, said tubes being spaced apart and supported by a suitable coupling 9. The inner tube is preferably longer 45 than the outer tube and projects above the level of the liquid. The outer tube terminates below the liquid level and is closed at the top by a ring 10. Said tube is provided 50 with a plurality of holes 11 near its upper end, through which the liquid fuel is supplied to the burner. The inner tube 8 supplies air to the flame, being provided at its lower end with a funnel 12 having a

screen 13 arranged therein and made preferably of gauze, whereby the air is strained. 55

Any overflow of fuel from the burner is caught by the flanged rim 2, as previously stated. If said fuel overflows from the latter receptacle, however, it is caught within the flanged tray or pan 14, the latter being 60 adjustably mounted on the screw threaded outer tube 7, whereby it may be moved up and down to partially obstruct the various openings in the base of the burner and hence regulate the air supplied to said burner. 65 Said tray also acts to shut off the light that would otherwise be radiated downwardly from said burner. This is an advantage under certain circumstances where said light is not desired. Said pan is provided 70 with a plurality of holes 15 through which the accumulated oil is drained into a cup or receptacle 16 also mounted on said tube 7. The oil within said receptacle is drained off through a pipe 17. 75

Oil is supplied to the burner through a pipe 18 which connects with the coupling 9 and which leads from a receptacle 19 having glass walls 20 through which the level of the oil may be observed. By regulating 80 the oil level in said receptacle, the oil level in the burner may be regulated accordingly. This regulation is affected by means of the needle valve 21 adapted to fit against a seat 22, said needle valve, even when in closed 85 position, permitting a small flow of oil through the openings 23, 24 therein (see Fig. 2). The oil is supplied to the valve through a suitable pipe 25. The needle valve moves up and down through a suitable stuffing box 26 and is provided with a short link 27 at its upper end by which it is connected to a lever 28 pivoted at the point 29 to a pair of arms 30 projecting upwardly from a suitable support 31. The movement 90 of the lever arm is controlled by a thermostatic device 32 of a well known construction, whereby upon an increase in the temperature of the medium surrounding said device, a fluid, preferably ether, within the same 100 expands and presses apart the thin, flexible walls thereof, thereby moving the lever arm to decrease the flow of oil. The upward movement of the left hand end of said lever arm is limited by an adjustable stop 33 105 having a notched periphery, whereby it may

be located in any of a number of angular positions by a resilient catch 34. Said adjustable stop may be marked with suitable characters in any arbitrary manner to indicate the degree of adjustment.

The invention is not to be limited to the details of construction described and illustrated, as various other forms may be devised which fall within the scope of the 10 pended claims.

What I claim is:

1. In a device of the class described, a burner having a conical recess adapted to contain liquid-fuel, a pair of concentric tubes 15 projecting into said recess from beneath, one terminating below the top of said recess and the other terminating above said top, a flanged rim around the outside of said burner to catch the overflow, and means for 20 varying the level of the liquid fuel within said conical recess to change the exposed area thereof.
2. In a device of the class described, a burner having a flanged rim, a supply tube 25 extending into said burner, a tray adjustably mounted on said tube, and an overflow cup also carried by said tube and arranged beneath said tray.
3. In combination, a burner having a recess for liquid-fuel, two tubes projecting cen- 30

trally into said recess, one of said tubes surrounding the other and spaced therefrom, and provided with an outlet whereby liquid-fuel supplied therethrough may be delivered to said recess, the other of said tubes being 35 provided at its lower end with an air strainer.

4. In combination, a supporting frame, a cylindrical partition thereon provided with a cap having an opening therein, a burner 40 also carried by said frame and terminating near said opening, an air supply tube and a fuel supply tube projecting into said burner, one of said tubes terminating below the level of the liquid therein and the other project- 45 ing above said level.

5. In combination, a burner having a fuel recess, a supply tube entering said recess, means for connecting said tube with a fuel supply, means for indicating the level of the 50 liquid in said burner, and means for automatically varying the flow of liquid-fuel to maintain a predetermined temperature.

In witness whereof I hereunto subscribe my name this 26th day of July, A. D., 1913. 55

WILLIAM N. FURTHMANN.
